UNITED STATES PATENT OFFICE.

ROBERT GIBB HUTCHISON, OF SITTINGBOURNE, ENGLAND.

PULP-STRAINER.

SPECIFICATION forming part of Letters Patent No. 578,515, dated March 9, 1897.

Application filed October 3, 1896. Serial No. 607,777. (No model.) Patented in England April 6, 1893, No. 7,112.

To all whom it may concern.

Be it known that I, ROBERT GIBB HUTCHISON, a subject of the Queen of Great Britain, and a resident of Sittingbourne, Kent county, England, have invented certain new and useful Improvements in Pulp-Strainers, (which have been patented in England, No. 7,112, dated April 6, 1893,) of which the following is a specification.

10 This invention relates to pulp-straining apparatus; and it consists of an apparatus in which the strainer is made of conical formation and is suspended within a vat with its upper surface below and parallel with the surface of the pulp, and its axis at an inclination, and with all the taper of its form disposed toward the part below its upper surface and where the density of the pulp is the greatest, and presenting an acting surface inclined to and acting against the flow of the pulp, and is so operated as to have continuous rapid combined endwise and vertical pulsations imparted to it, which produce a powerful vacuous tendency within the strainer, effective in causing the pulp to stream through the strainer much more rapidly than in existing strainers and in automatically keeping its outside clean and its slits from being choked.

30 On the accompanying drawings, Figure 1 represents a side elevation of the apparatus. Fig. 2 represents an end elevation of the discharge end in section on line *c d*, Fig. 4. Fig. 3 represents a sectional elevation of the other end on line *e f*, Fig. 6. Fig. 4 represents a plan taken as at right angles to the axis of the strainer. Fig. 5 represents a partial sectional elevation on line *g h*, Fig. 1; and Fig. 6 represents a sectional elevation on line *i j*, Fig. 4.

40 A is the strainer, and B is the vat, which are respectively constructed and adapted to coöperate as hereinafter described, and C is the means for giving the desired motion to the strainer within the vat.

45 The strainer A is of conical formation, circular at all sections at right angles to its axis, and is constructed with a frame consisting of a closing end piece *a'*, coned at *a²* and flanged at *a³* at its smaller end, and of an annular end piece *a⁴*, coned at *a⁵*, flanged at *a⁶*, and connected by arms *a⁷* to a central boss *a⁸* at

its outlet end, which end pieces *a'* *a⁴* respectively serve to support two correspondingly-coned rings *a⁹* *a¹⁰*, which are connected by longitudinal ribs *a¹¹*, to the outer surfaces of 55 which and of the rings *a⁹* *a¹⁰* sectoral conical strainer-plates *a¹²* are secured by bolts *a¹³*.

The strainer-plates *a¹²* are perforated with closely-adjacent fine slits *a¹⁴*, running longitudinally of the strainer, the fineness of the 60 slits being regulated by the class of fiber intended to be dealt with in the machine.

The strainer A is suspended within the vat B (*vide* Fig. 5) with its upper surface horizontal and its axis at an inclination and its 65 under surface at a correspondingly-increased inclination, the bottom *b'* of the vat being made of a corresponding inclination and formation to that of the under part of the strainer and its upwardly-extending sides *b²* being 70 parallel. (*Vide* Fig. 5.)

In the ends *b³* *b⁴* of the vat openings *b⁵* *b⁶* are made concentric with the axis of the strainer and of larger diameters than the adjacent ends of the strainer, and in the planes 75 of these openings and concentric therewith the strainer ends are supported by a shaft *d*, as hereinafter described, the spaces between the strainer ends and the rims of the vat end openings being then closed by flexible annular diaphragms *e*, which are secured to the adjacent parts by rings *a¹⁵* and bolts *a¹⁶* and serve to keep the pulp within the vat, while permitting of the movements of the strainer.

The shaft *d* is arranged at an inclination 85 with its axis coincident with that of the strainer and is pivotally supported externally of and at the delivery end of the vat by an eyeleted collar *d'* and a link *d²* from an adjustable center *f*, supported by the outlet-casing *f'*, and at the other end is mounted on an eccentric *c'* on the actuating-shaft C. The strainer end *a'* abuts against a collar *d³* on the shaft *d*, which is reduced in diameter at *d⁴*, and abuts against an inner flange *a¹⁷* at 95 the end of the boss *a⁸* of the strainer end *a⁴*.

In the outlet-casing *f'* is formed an end opening *f²*, concentric with the axis of the shaft and of larger diameter than and in the plane of the boss *a⁸*, the space between the 100 boss and the rim of the opening being closed by a flexible annular diaphragm *f³*, which is

secured to the adjacent parts by rings f^4 and bolts f^5 and serves the like purposes to those served by the diaphragm e .

The shaft C is mounted in bearings c^2 , carried by a stool-bracket c^3 , which also supports the adjacent end of the vat and is provided with fast and loose pulleys c^4 c^5 and with a regulating fly-wheel c^6 . The throw of the eccentric c' is preferably between about one-eighth to one-quarter of an inch, and the shaft C revolves at about five hundred to six hundred revolutions per minute.

The outlet end of the vat is supported by a stool b^7 and at its lowest point is connected with a pipe b^8 , serving to drain off the refuse and unprepared pulp, fiber, or material that will not pass through the strainer. The pipe b^8 is provided with two cocks b^9 b^{10} , the former of which can be used when the strainer is in operation for leading the discharge to an auxiliary apparatus, where it can be again utilized.

The outlet f^6 of the casing f' is connected with a conduit f^7 , leading to the service or regulating box f^8 . The strained pulp gravitates in a regular discharge of strained and finished pulp, ready for the paper-making machine, to the outlet f^6 and finds its level in the casing f' , according to the height of the regulating-slue f^9 of the service-box, which is always lower than the level of the pulp in the vat, (indicated by the dotted line g in Fig. 6,) so as to create the necessary fall, and the vat is kept continuously supplied with pulp, so as to keep the required head.

The casing f' is also formed with two hand-holes f^{10} at the end and with two others at the top, each thereof being closed by a cover f^{11} , secured by a screw f^{12} , engaging with a bridge-piece f^{13} , hinged to the casing, as at f^{14} , the arrangement being such as to permit of the ready removal of the covers, when required, to wash out and clean the interior of the strainer, and of the ready replacement thereof.

By such means, when the apparatus is in operation, steady continuous rapid combined endwise and vertical pulsating movements are imparted to the strainer, the vertical movements being accommodated by the give and take of the diaphragms e f^3 , which latter also, together with the linked connections d' d^2 of the shaft d , accommodate and permit of the endwise reciprocations of the shaft and strainer. The inclined disposition of the bottom of the vat tends to produce a natural gravitation of the pulp to the outlet, and the inclined disposition of the conical strainer, with its top surface horizontal, disposes all the taper thereof toward the lower part, where the density of the pulp is the greatest, and

the peculiar endwise motion imparted to the strainer causes it to have a suctional action on the pulp when receding and to present an acting surface inclined to and against the flow of the pulp when returning, in contradistinction to the slipping motion of cylindrical strainers reciprocating in arcs coincident with their radii, as hitherto used. This peculiar motion of the strainer is also effective in automatically keeping its outside perfectly clean and its slits free from all choking, which is a defect inherent to such cylindrical strainers.

In lieu of the combined endwise and vertical motion I may impart to the inclined conical strainer a combined endwise and lateral motion, or I may arrange it with its axis at a greater or less inclination than aforesaid or horizontally or vertically and may impart to it simply a reciprocating endwise motion or a conical motion about its bottom as a center, if its axis be arranged vertically.

I claim as my invention—

1. A pulp-strainer apparatus consisting of a vat a conical strainer suspended therein with its upper surface below and parallel with the surface of the pulp, and its axis at an inclination, and with all the taper of its form disposed toward the part below its upper surface and where the density of the pulp is the greatest, and presenting an acting surface inclined to and acting against the flow of the pulp, and means for imparting continuous rapid combined endwise and radial pulsations to said strainer, as set forth.

2. In a strainer, in combination, a shaft d , shouldered at d^3 , and reduced at d^4 , coned strainer ends a' , a^4 , supported by the shaft and held against the abutments thereof, end rings a^9 , a^{10} , connecting-rails a^{11} , and conical strainer-plates a^{12} , as set forth.

3. In combination, a shaft d , shouldered at d^3 , and reduced at d^4 , coned strainer ends a' , a^4 , supported by the shaft and held against the abutments thereof, end rings a^9 , a^{10} , connecting-rails a^{11} , and conical strainer-plates a^{12} , a vat B , having a semiconical inclined bottom b' , and through end openings b^5 , b^6 , and an outlet f' , flexible diaphragms e , f^3 , connecting the strainer with the vat and the outer casing, and means of pivotally supporting the shaft at one end, and of imparting to it at the other end combined endwise and radial pulsating movements, as set forth.

In witness whereof I have hereunto set my hand in presence of two witnesses.

ROBERT GIBB HUTCHISON.
